UNITED STATES PATENT OFFICE

2,644,421

MUSIC-BOX CABINET

Louis Arceo, New York, N. Y.

Application September 18, 1951, Serial No. 247,091

9 Claims. (Cl. 116—100)

1

This invention relates to new and useful improvements in a music box cabinet.

More specifically, the present invention proposes the construction of an improved cabinet which can be hung on a baby's crib or bathinette or on a chair in close proximity to such articles of baby furniture for containing a baby's toilet articles such as talcum powder, baby oil and the like and which includes a music box for playing a predetermined tune when the cabinet is opened for the removal of the toilet articles therefrom.

Still another object of the present invention proposes the formation of a cabinet consisting of a main body having hooks adjustably secured to the rear thereof in a manner to be used for supporting the cabinet at a desired elevation on a crib, bathinette, chair or other article of furniture.

Another object of the present invention proposes providing the main body internally with superimposed shelves upon which toilet articles can be placed to be readily accessible when a pair of pivotally mounted doors which normally close the open front of the main body have been pivoted to an open position.

A further object of the present invention proposes mounting the music box on the top of the main body and to provide the music box with a movably mounted control plate which normally holds a spring pressed plunger in a raised position, but which plate can be pulled outward from the music box releasing the plunger to be resiliently urged downward so that the music box will be free to play its predetermined tune.

The present invention further proposes connecting a slidably mounted control member to the control plate and which control member is resiliently urged in a direction to hold the control plate in a position in which it holds the spring pressed plunger raised in a manner to keep the music box from playing when both of the doors are in their closed position.

Still further, the present invention proposes arranging the doors of the cabinet so that the one door must be opened before the other door can be opened in a manner to obtain a desired operation of the music box.

Still another object of the present invention proposes providing the control plate with an elongated slot in alignment with the music box plunger in a manner so that as the control plate is moved outward the plunger will be momentarily released and then raised again to shut off the music box after sounding a short audible signal.

2

Another object of the present invention proposes the provision of a dashpot operated means controlled by the accidental opening of the said one cabinet door for slowly moving the control member and control slide in a manner to cause the slot of the control slide to move slowly past the lower end of the plunger to sound the audible signal and draw attention to accidentally opened cabinet door.

10 A further object of the present invention proposes the provision of means controlled by the other of the cabinet doors, when both of the doors are being opened, and which functions completely independently of the dashpot operated means referred to in the paragraph next above to move the control slide to completely withdraw the control plate and release the plunger so that the music box will be freed to play its predetermined tune.

15 It is a further object of the present invention to construct a cabinet of the type referred to which is simple and durable, which is effective for its intended purposes and which can be manufactured and sold at a reasonable cost.

20 For further comprehension of the invention, and of the objects and advantages thereof, reference will be had to the following description and accompanying drawing, and to the appended claims in which the various novel features of the invention are more particularly set forth.

25 On the accompanying drawing forming a material part of the present disclosure:

Fig. 1 is an isometric view of the cabinet constructed in accordance with the present invention.

30 Fig. 2 is a front elevational view of Fig. 1, but with the doors shown in the open position and broken away to shorten the width of the figure.

Fig. 3 is a rear elevational view of the top portion of Fig. 1.

35 Fig. 4 is a partial vertical sectional view taken on the line 4—4 of Fig. 2.

Fig. 5 is an enlarged partial vertical sectional view taken on the line 5—5 of Fig. 1.

40 Fig. 6 is an enlarged horizontal sectional view taken on the line 6—6 of Fig. 1.

Fig. 7 is a partial transverse vertical sectional view taken substantially on the line 7—7 of Fig. 6.

45 Fig. 8 is a view similar to Fig. 6 showing the position of the parts when the first door is accidentally opened or is not properly closed.

Fig. 9 is another view similar to Fig. 6 showing the position of the parts when the two doors are moved to their open position.

50 55

The cabinet, according to the present invention, includes a main body 15 constructed to have a rear wall 16, a top wall 17, a bottom wall 18 and spaced side walls 19. The main body 15 has an open side which is considered to be an open front side which is normally closed by a pair of adjacent doors 20 and 21. The doors 20 and 21 are supported to swing open and closed positions on hinges 22. The hinges 22 are secured to the outer edges of the doors 20 and 21 and the front vertical edges of the side walls 19. The inner edge of the door 21 carries a projecting portion 21^a which is overlapped, in the closed position of the doors shown in Figs. 1 and 6, by a complementary projecting portion 20^a of the door 20 which requires that the door 20 be opened before the door 21 can be opened. Conversely, the projecting portions 20^a and 21^a require that the door 21 be completely closed, when both of the doors are being closed.

Means is provided for holding the doors 20 and 21 in their closed position and structural details of such means as it is applied to the door 20 are shown in Fig. 5 and it is understood that similar means are used on the door 21. The door holding means comprises a small tubular casing 23 which is fixedly mounted within a hole 24 extended in from the bottom edge of the door 20 adjacent its free inner vertical edge. The casing 23 slidably supports a small plunger 25 which is urged to an extended position by an expansion spring 26 contained in the casing 23. The extended end of the plunger 25 is rounded and is received within a keeper element 27 for holding the respective door 20 or 21 in its closed position. The keeper elements 27 for the doors 20 and 21 are mounted on a forwardly projected ledge 18^a of the bottom wall 18 which is located beneath the doors 20 and 21. As the doors 20 and 21 are opened and closed, the plungers 25 snap into and out of the keeper element 27 against the holding action of the springs 26. Knobs 28 are mounted on the outer faces of the doors 20 and 21 by which the doors can be pivoted between open and closed positions against the holding action of the spring pressed plungers 25.

Superimposed shelves 29 are mounted within the cabinet for having baby's toilet articles—such as cans of talcum powder, bottles of baby oil, containers of cotton and the like—placed thereon. The shelves 29 are adjustably positioned within the main body 15 of the cabinet by having their ends rested on pegs 30 selectively engageable with aligned sets of complementary holes 31 formed in the inner faces of the side walls 19, see Figs. 2 and 4. Shifting the vertical positions of the shelves 29 within the main body 15 varies their vertical spacing to accommodate articles of different heights.

Hooks 32 are attached to the rear wall 16 of the main body 15 and project above the top of the cabinet to be used for supporting the cabinet on a baby's crib, bainnette or on a chair in close proximity to such articles of baby furniture so that the articles contained in the cabinet will be readily available for use when bathing or changing the baby. At their bottom ends behind the main body 15 of the cabinet, the hooks 32 are formed with flattened portions 33 each formed with a pair of holes for the passage of screws 34. The outer face of the rear wall 16 of the main body 15 is formed with vertical sets of spaced holes 35 matching the spacing of the screw holes of the flattened portions 33. The holes 35

are provided for selectively receiving the screws 34 to vary the attachment of the hooks 32 to the rear wall 16 of the cabinet and so support the cabinet at the desired elevation on the piece of baby furniture.

Fixedly mounted within the main body 15 slightly below the top wall 17 there is a partition 36 which divides off a compartment 37 for a music box 38 and its control mechanism. The front of the compartment 37 is closed by a wall 39 for hiding the music box 38 and its control mechanism when the doors 20 and 21 are in the open position shown in Figs. 2 and 9. However, the wall 39 can be omitted if desired. The wall 39 is preferably formed with a plurality of vertically spaced horizontally elongated slots 40 for permitting the music from the music box 38 to emanate from the compartment 37 in the open position of the doors 20 and 21.

The music box 38 is mounted on the inner face of the top wall 17 of the main body 15 midway between the side walls 19. The music box 38 is of conventional construction and includes the usual spring motor, not shown, for turning a drum, not shown, having a plurality of radially extended pins for plucking the tines of a music comb, not shown, for playing a predetermined tune which in the present case might be a nursery rhyme set to music, a lullaby or similar musical tune. Construction details of the spring motor, drum and music comb are not given in this specification as such details are generally known in the art and form no part of the present invention. The usual key 41 for winding the spring of the music box 38 is exposed through the top wall 17 of the main body so that the music box 38 can be wound up without having to open the doors 20 and 21.

The music box 38 includes the usual vertically slidable plunger 42 which is resiliently urged downward by a spring 43, see Fig. 7. When the plunger 42 is in its lowered position the music box 38 is free to play its predetermined tune. On the other hand, when the plunger 42 is raised against the action of the spring 43, the music box is shut off or inoperative. The music box 38 has spaced superimposed bottom walls 44 and 45 which form between them a slideway 46 for a control plate 47. The bottom of the plunger 42 is exposed through a hole 48 in the bottom wall 44 to be engaged by the control plate 47. When the control plate 47 is pushed completely inward, as shown in Figs. 6 and 7, the control plunger 42 is held in a raised position against the action of the spring 43 to keep the music box 38 inoperative or shut off. On the other hand, when the control plate 47 is pulled outward so that its inner end passes the plunger 42, as shown in Fig. 9, the plunger 42 is freed to be urged downward by its respective spring 43 to free the music box 38 to play its predetermined tune. Music boxes having spring pressed plungers arranged as described are in common use in the so called "musical" powder boxes, perfume atomizers and similar articles wherein the music boxes are released to play the moment they are picked up off the surfaces on which they are resting.

At one point adjacent its free inner edge and in alignment with the bottom end of the plunger 42, the control plate 47 is formed with an elongated slot 49. The slot 49 stops short of the inner edge of the control plate 47 and is provided for a purpose to be described as this specification proceeds.

Attached to the control plate 47, there is a

control member 50 for moving the control plate 47 and which is resiliently urged to a position in which the control plate 47 is completely pushed inward to hold the plunger 42 in its raised inoperative position. The control member 50 is of U-shape and has one long arm 50^a, a short arm 50^b and an intermediate arm 50^c. The free end of the short arm 50^b of the control member 50 is secured to the projected end of the control plate 47 by means of a pin 51. The long arm 50^a of the control member 50 is slidably supported in complementary brackets 52 which extends forwardly from the rear wall 16 of the main body 15. Extending rearward from the long arm 50^a at a point between the brackets 52, there is a pin 53. A similar pin 54 is mounted on the rear wall 16 between the brackets 52. A contraction spring 55 has its ends attached to the pins 53 and 54 urging the control member 50 in a direction in which the control plate 47 will be in its fully pushed in position shown in Figs. 6 and 7. The spring 55 is a relatively weak one and exerts a force just sufficient to push the control plate 47 completely inward against the action of the spring 43 of the plunger 42.

Means is provided and controlled by accidental opening or improper closing of the door 20 for moving the control member 50 against the action of the spring 55 to cause the control plate 47 to be moved outward passing its slot 49 beneath the plunger 42 to momentarily release the music box to sound an audible signal to draw attention to the door 20. The means functions to stop the control plate 47 in the position shown in Fig. 8, in which the material of the control plate 47 between its free inner edge and the adjacent end of the slot 49 will raise the plunger 42 and shut off the music box 38 so that it will not play itself out with only the door 20 in its open position.

The means referred to in the paragraph next above consists of a bell crank 56 which is pivotally supported at the junction of its arms on a boss 57 by means of a pin 58. The boss 57 extends upward from the top face of the partition 36. One arm 56^a of the bell crank 56 is engaged at its free end behind the free end of the long arm 50^a of the control member 50. The other arm 56^b of the bell crank 56 is extended through an elongated horizontal slot 59 formed in the wall 39 so that the free end of the arm 56^b is engaged by the inner face of the door 20. A contraction spring 60 operates between a pin 61 mounted on the adjacent bracket 52 and the free end of the arm 56^a of the bell crank 56. The spring 60 is of a tension slightly greater than the tension of the spring 55 but of insufficient tension to open the door 20 against the action of its holding means.

When the door 20 is closed, the door functions to hold the bell crank 56 in the pivoted position shown in Fig. 6 against the tension of the spring 60. That position of the bell crank 56 leaves the spring 55 to urge the control member 50 to a position in which the control plate 47 will retain the music box 38 in its off position; the position shown in Figs. 6 and 7.

On the other hand, if the door 20 should be accidentally opened or be improperly closed, the tension of the spring 60 will pivot the bell crank 56 to the position shown in Fig. 8 in which the free end of the arm 56^b will be extended through the slot 59. Such movement of the bell crank 56 will cause the arm 56^a to slide the control member 50 against the action of its spring 55 and pull outward on the control slide 47.

During such outward movement, the slot 59 of the control plate 47 moved beneath the plunger 42 momentarily releasing the plunger 42 to move downward under the action of its spring 43 momentarily releasing the music box 38 to sound a short audible signal drawing attention to the accidentally opened or improperly closed door 20.

Means is provided in connection with the bell crank 56 for delaying the action of the spring 60 and for stopping the movement of the bell crank 56 in a position in which the control plate 47 will have its material between its inner edge and the inner end of the slot 49 immediately below the bottom end of the plunger 42 raising that plunger to shut off the music box 38 after the short warning signal has been sounded. That delaying and stopping means comprises a dashpot 62 having a hollow casing 63 fixedly mounted on the partition 36. Slidably disposed within the casing 63, there is a piston 64 from which a concentric rod 65 projects to the exterior of the casing 63. The free end of the rod 65 carries a pin 66 which engages an elongated slot 67 formed in the arm 56^a of the bell crank. The pin and slot function to connect the bell crank 56 and the rod 65 so that pivotal movements of the bell crank will cause the piston 64 to be moved to and fro within the casing 63.

The piston 64 is formed with large holes 68 for the passage of air as the piston 64 moves back and forth within the casing 63. Fixedly secured to the face of the piston 64 remote from the side from which the rod 65 extends, there is a flexible member 69 of rubber or other flexible material. The flexible member 69 is formed with holes 70 aligned with the holes 68 of the piston 64. The holes 70 are of a smaller diameter than the diameter of the holes 68, as clearly shown in Figs. 6, 8, and 9. The casing 63 on the side of the piston 64 remote from the flexible member 69 is formed with holes for insuring that the piston 64 will not become air locked within the casing 63.

When the rod 65 is pushed inward under the action of the spring 60 which pivots the bell crank 56, the flexible member 69 will be forced against the adjacent face of the piston 64 so that the small holes 70 of the flexible member will restrict the flow of air through the larger holes 68 of the piston 64. That will cause the piston 64 to move slowly within the casing 63 causing the bell crank 56 to be slowly pivoted by the spring 60 to slowly push the control member 50 against the action of its spring 55. The control plate 47 will be slowly pulled out so that the slot 49 will move slowly past the lower end of the plunger 42 insuring that the plunger will be lowered a sufficient length of time affording the music box 38 an ample opportunity to sound the audible alarm. When the piston 64 reaches the other end of the casing 63, as shown in Fig. 8, the action of the spring 60 will be arrested stopping the outward movement of the control plate 47 in the position shown in that Fig. 8 in which the material of the plate between its inner end and the adjacent end of the slot 49 will be below the plunger 42. That will cause the plunger 42 to be raised against the action of the spring 43 to shut off the music box 38 notwithstanding that the door 20 is still open. Thus, the music box will be restrained from completely unwinding itself with only the one door open.

When the door 20 is properly closed, the bell crank 56 will be pivoted against the action of the spring 60 back to the position shown in Fig. 6.

On that return movement of the bell crank the air passing through the holes 68 of the piston 64 blows the peripheral edges of the flexible member 69 away from the adjacent face of the piston 64 so that the air will pass rapidly through those holes permitting the piston 64 to slide freely within the cylinder 63 on the back movement of the bell crank. Such back movement of the bell crank 56 released the control member 50 to be urged back by its spring 55 to return the control plate 47 to its starting position shown in Fig. 6.

Arranged to be controlled by the door 21, there is means to release the plunger 42 to free the music box 38 to play its predetermined tune as long as its spring is under tension, when both of the doors 20 and 21 are opened for the removal of the baby's toilet articles from the interior of the cabinet. The means controlled by the door 21 includes a bell crank 72 which is pivoted at the junction of its arms 72^a and 72^b by means of a pin 73 upon a boss 74 which extends upward from the partition 36. The free end of the arm 72^a of the bell crank 72 underlies the intermediate arm 50^c of the control member 50 and carries an upstanding peg 75 which is engaged behind that intermediate arm 50^c.

A rod 76 is longitudinally slidably supported in brackets 77 which extend upward from the partition 36. An intermediate portion of the rod 76 overlies the free end of the arm 72^b of the bell crank. The rod 76 is formed with a depending pin 78 which engages an elongated slot 79 formed in the arm 72^b of the bell crank 72 for causing the bell crank 72 to be pivoted in one direction or the other as the rod 76 is moved in and out.

The front end of the rod 76 is extended through a complementary aperture 80 formed in the wall 39 so that the front end of that rod will be engaged by the inner face of the door 21 to hold the rod in a pushed in position, see Figs. 6 and 8, when the door 21 is closed. To the rear of the pin 78, the rod 76 is formed with an integral collar 81 and an expansion spring 82 is engaged about the rod 76 and operates between the adjacent faces of the collar 81 and the adjacent bracket 77 to cause the front end of the rod to be projected through the aperture 80 when the door 21 is opened, see Fig. 9.

The expansion spring 82 is similar to the spring 60 in that it has a tension greater than the tension of the spring 55 so that it is capable of overcoming that spring 55 and move the control member 50. However, the spring 82 does not exert a force sufficient to open the door 21 against action of the means which holds that door closed.

When the door 21 is opened, it being appreciated of course that the door 20 must be opened first, the spring 82 will immediately function to extend the rod 76 to the position shown in Fig. 9. That action will pivot the bell crank 72 causing the peg 75 to pull on the control member 50 against the action of its spring 55 and pull the control plate 47 out to the position shown in Fig. 9. The plunger 42 will be completely released and free the music box to play its predetermined tune as long as its self-contained spring is under tension and the doors 20 and 21 remain open. When the door was opened, the bell crank 56 was moved by its spring 63 to the position shown in Fig. 9, but that bell crank was inoperative to move the control plate 47 as the same was moved to its fully extended position by the action of the bell crank 72.

When the doors 21 and 20 are reclosed in that

succession, the bell cranks 72 and 56 will be pivoted back to their starting position shown in Fig. 6 freeing the control member 50 to be urged back to its starting position by the spring 55 pushing in on the control side 47 to shut off the music box 38.

From the foregoing description, it is apparent that the present invention proposes a novel cabinet for mounting upon a baby's crib, bath-inette or other article of furniture for conveniently containing all of the toilet articles required when bathing or changing the baby. However, while the features of the present invention are described in connection with a cabinet for containing a baby's toilet articles that is by way of illustration only as those features can be incorporated in any desired type of cabinet or other articles of furniture having openable doors without departing from the scope and intent of the present disclosure.

While I have illustrated and described the preferred embodiment of my invention, it is to be understood that I do not limit myself to the precise method herein disclosed and the right is reserved to all changes and modifications coming within the scope of the invention as defined in the appended claims.

Having thus described my invention, what I claim as new and desire to secure by United States Letters Patent is:

1. A cabinet of the class described, comprising a main body, a pair of adjacent pivotally mounted doors closing the open side of said main body, a music box mounted within the top portion of said main body having a spring pressed plunger urged in a direction to free said music box to play, a control plate slidably mounted in said music box and normally holding said plunger in a position in which said music box is inoperative, and a spring pressed plunger means controlled by opening of at least one of said doors to move downwardly and free said plunger to release said music box to play at least a portion of its predetermined tune.

2. A cabinet of the class described, comprising a main body, a pair of adjacent pivotally mounted doors closing the open side of said main body, a music box mounted within the top portion of said main body having a spring pressed plunger urged in a direction to free said music box to play, a control plate slidably mounted in said music box and normally holding said plunger in a position in which said music box is inoperative, and a spring pressed plunger means controlled by opening of at least one of said doors to move downwardly and free said plunger to release said music box to play at least a portion of its predetermined tune, and means holding said doors in their closed position.

3. A cabinet of the class described, comprising a main body, a pair of adjacent pivotally mounted doors closing the open side of said main body, a music box mounted within the top portion of said main body having a spring pressed plunger urged in a direction to free said music box to play, a control plate slidably mounted in said music box and normally holding said plunger in a position in which said music box is inoperative, and a spring pressed plunger means controlled by opening of at least one of said doors to move downwardly and free said plunger to release said music box to play at least a portion of its predetermined tune, and knobs mounted on said doors providing a grip for opening the same.

4. A cabinet of the class described, comprising

a main body having an open side, a pair of adjacent pivotally mounted doors closing the open side of said main body, said doors being restricted so that one door must be opened before the other door can be opened, a music box mounted within the top portion of said main body and having a spring pressed plunger which moves downward freeing said music box to play a predetermined tune, a control plate slidably mounted in said music box and normally holding said plunger in a raised position in which said music box is inoperative, a slidably mounted control member connected to said control plate and resiliently urged to a position in which said control plate retains said plunger in a raised position, means controlled by accidental opening of said one door for moving said control member to in turn move said control plate to free and again raise said plunger to cause said music box to sound a short audible warning signal to draw attention to the doors, and means controlled by said other door when both of said doors are opened to move said control member to withdraw said control plate and release said plunger freeing said music box to play its predetermined tune.

5. A cabinet of the class described, comprising a main body having an open side, a pair of adjacent pivotally mounted doors closing the open side of said main body, said doors being restricted so that one door must be opened before the other door can be opened, a music box mounted within the top portion of said main body and having a spring pressed plunger which moves downward freeing said music box to play a predetermined tune, a control plate slidably mounted in said music box and normally holding said plunger in a raised position in which said music box is inoperative, a slidably mounted control member connected to said control plate and resiliently urged to a position in which said control plate retains said plunger in a raised position, means controlled by accidental opening of said one door for moving said control member to in turn move said control plate to free and again raise said plunger to cause said music box to sound a short audible warning signal to draw attention to the doors, and means controlled by said other door when both of said doors are opened to move said control member to withdraw said control plate and release said plunger freeing said music box to play its predetermined tune, and means holding said doors in a closed position against the actions of said door controlled means.

6. A cabinet of the class described, comprising a main body having an open side, a pair of adjacent pivotally mounted doors closing the open side of said main body, said doors being restricted so that one door must be opened before the other door can be opened, a music box mounted within the top portion of said main body and having a spring pressed plunger which moves downward freeing said music box to play a predetermined tune, a control plate slidably mounted in said music box and normally holding said plunger in a raised position in which said music box is inoperative, a slidably mounted control member connected to said control plate and resiliently urged to a position in which said control plate retains said plunger in a raised position, means controlled by accidental opening of said one door for moving said control member to in turn move said control plate to free and again raise said plunger to cause said music box to sound a short audible warning signal to draw attention to the doors, and means controlled by

said other door when both of said doors are opened to move said control member to withdraw said control plate and release said plunger freeing said music box to play its predetermined tune, said first door controlled means including an elongated slot in said control plate aligned with said plunger and a spring pressed pivotally mounted bell crank operating between the said one door and said control member.

7. A cabinet of the class described, comprising a main body having an open side, a pair of adjacent pivotally mounted doors closing the open side of said main body, said doors being restricted so that one door must be opened before the other door can be opened, a music box mounted within the top portion of said main body and having a spring pressed plunger which moves downward freeing said music box to play a predetermined tune, a control plate slidably mounted in said music box and normally holding said plunger in a raised position in which said music box is inoperative, a slidably mounted control member connected to said control plate and resiliently urged to a position in which said control plate retains said plunger in a raised position, means controlled by accidental opening of said one door for moving said control member to in turn move said control plate to free and again raise said plunger to cause said music box to sound a short audible warning signal to draw attention to the doors, and means controlled by said other door when both of said doors are opened to move said control member to withdraw said control plate and release said plunger freeing said music box to play its predetermined tune, said first door controlled means including an elongated slot in said control plate aligned with said plunger and a spring pressed pivotally mounted bell crank operating between the said one door and said control member, and a dash pot means restricting the movement of said bell crank when pivoted to move said control plate to free said plunger.

8. A cabinet of the class described, comprising a main body having an open side, a pair of adjacent pivotally mounted doors closing the open side of said main body, said doors being restricted so that one door must be opened before the other door can be opened, a music box mounted within the top portion of said main body and having a spring pressed plunger which moves downward freeing said music box to play a predetermined tune, a control plate slidably mounted in said music box and normally holding said plunger in a raised position in which said music box is inoperative, a slidably mounted control member connected to said control plate and resiliently urged to a position in which said control plate retains said plunger in a raised position, means controlled by accidental opening of said one door for moving said control member to in turn move said control plate to free and again raise said plunger to cause said music box to sound a short audible warning signal to draw attention to the doors, and means controlled by said other door when both of said doors are opened to move said control member to withdraw said control plate and release said plunger freeing said music box to play its predetermined tune, said latter mentioned door controlled means including a spring pressed slidably mounted rod and a pivotally mounted bell crank operating between said rod and said slidably mounted control member, said rod being rotatively retained in an

inoperative position by the said other door when in its closed position.

9. A cabinet of the class described, comprising a main body having an open side, a pair of adjacent pivotally mounted doors closing the open side of said main body, said doors being restricted so that one door must be opened before the other door can be opened, a music box mounted within the top portion of said main body and having a spring pressed plunger which moves downward freeing said music box to play a predetermined tune, a control plate slidably mounted in said music box and normally holding said plunger in a raised position in which said music box is inoperative, a slidably mounted control member connected to said control plate and resiliently urged to a position in which said control plate retains said plunger in a raised position, means controlled by accidental opening of said one door for moving said control member to in turn move 15 said control plate to free and again raise said

5 control member to withdraw said control plate and release said plunger freeing said music box to play its predetermined tune, said music box and its related control means being mounted within a compartment in the top of said main body divided off by a fixedly mounted partition 10 within said main body.
